COMBINED CUP AND BASE THEREFOR

Robert Makara, 29 Orange Drive, Jericho, N.Y.

Filed Mar. 19, 1964, Ser. No. 79,090

Term of patent 14 years

(Cl. D44—9)

FIG. 1 is an exploded perspective view of the combined cup and base therefor showing my new design;

FIG. 2 is a bottom perspective view of the cup;

FIG. 3 is a top plan view;

FIG. 4 is a side elevational view, and

FIG. 5 is a similar view on a slightly reduced scale with the base in an inclined position and shown partly in section.

I claim:

The ornamental design for a combined cup and base therefor, as shown and described.
